CLAIM

The ornamental design for a magazine for firearm, as shown and described.

DESCRIPTION

FIG. 1 is a perspective view of a magazine for firearm according to the present design;

FIG. 2 is a 180 degree rotated perspective view of FIG. 1; FIG. 3 is a front plan view of the design shown in FIG. 1; FIG. 4 is a rear plan view of the design shown in FIG. 1. FIG. 5 is a left side plan view of the design shown in FIG. 1;

FIG. 6 is a right side plan view of the design shown in FIG. 1;

FIG. 7 is a top view of the design shown in FIG. 1; and, FIG. 8 is a bottom view of the design shown in FIG. 1; The broken lines depict portions of the magazine for firearm that form no part of the claimed design.

1 Claim, 6 Drawing Sheets
